(57) **CLAIM**

The ornamental design for a basketball court clipboard, as shown and described.

DESCRIPTION

FIG. 1 is a plan view of a basketball court clipboard; and, FIG. 2 is a side plan view of the basketball court clipboard. The broken lines in FIGS. 1 and 2 are included for the purpose of showing portions of the basketball court clipboard that form no part of the claimed design.

1 Claim, 2 Drawing Sheets**FIG. 1**

FIG. 2
